UNITED STATES PATENT OFFICE.

STUART OTTO, OF WILTON, CONNECTICUT, AND JACK CARL JANKUS, OF SCRANTON, PENNSYLVANIA, ASSIGNEES, BY DIRECT AND MESNE ASSIGNMENTS, TO ICELESS AUTOMATIC REFRIGERATOR COMPANY, A CORPORATION OF DELAWARE.

EVAPORATOR FOR REFRIGERATING APPARATUS.

Application filed January 18, 1923, Serial No. 613,442. Renewed May 5, 1927.

This invention is an improvement in evaporators for liquefied refrigerant, and adapted for use in refrigerators, cooling chambers, or the like. The invention relates particularly to that type in which the evaporator serves as a receiver for the liquefied refrigerant, and is alternately filled during the liquefying of the gas under pressure, and then slowly emptied by reduction of the pressure of the gas and the resulting evaporation of the liquid to produce the desired cooling effect.

In refrigerating systems of the absorption type it sometimes happens, due to improper regulation, failure of condenser water, or other causes, that some of the absorber liquid which is far less volatile than the liquefied gas, passes through the condenser and collects in the evaporator where it interferes with the proper and efficient operation of the system.

One important feature of our invention resides in the novel means employed for automatically effecting a withdrawal of liquid at intervals from the evaporator, and returning it to the absorber, so as to prevent the accumulation of liquid of a character which is not readily volatile in the evaporator.

In carrying out the invention, we provide a float within the evaporator and serving to operate a valve, whereby at the beginning of the cooling or evaporating period, liquid will be drawn from the bottom of the evaporator, whereas during the main portion of the cooling or evaporating period, only gas resulting from the evaporation will be withdrawn from the evaporator.

This invention involves several features of construction and other advantages will be pointed out hereafter, or will be apparent from a consideration of the forms illustrated in the drawings. In these drawings:

Fig. 1 is a front elevation of a refrigerator showing our improved evaporator serving as a central vertical partition therein.

Fig. 2 is an enlarged vertical section of the evaporator and in a plane at right angles to the plane of Fig. 1, said plane being indicated by the line 2—2 of Fig. 3.

Fig. 3 is a section on the line 3—3 of Fig. 2, a portion of one of the trays being broken away.

Fig. 4 is a sectional detail on the line 4—4 of Fig. 2, but on a larger scale. 55

Fig. 5 is a front view of a refrigerator showing a different construction of evaporator.

Fig. 6 is a horizontal section on the line 6—6 of Fig. 5. 60

Fig. 7 is a vertical section on a larger scale through the evaporator, and in a plane parallel to that of Fig. 5, said plane being indicated by the line 7—7 of Fig. 8.

Fig. 8 is a section on the line 8—8 of Fig. 7. 65

Fig. 9 is a front elevation of a refrigerator having a type of evaporator adapted to be used in the ordinary ice box.

Fig. 10 is a larger view of the evaporator 70 shown in Fig. 9, certain of the parts being taken in section on the line 10—10 of Fig. 11 and

Fig. 11 is a section on the line 11—11 of Fig. 10. 75

Our improved evaporator is particularly adapted for use in that system in which a liquefiable gas is driven out of an absorbent liquid by heating of the liquid in a still, and the gas passes under the pressure of the still, 80 through a condenser where it is cooled to such a point that it liquefies under pressure. The liquefied gas is delivered to the evaporator. Upon the shutting off of the heat from the still and the cooling of the absorbent 85 liquid therein, the liquefied gas in the evaporator is caused to evaporate and pass back into the liquid in the still which now serves as an absorber. The liquefied gas during its evaporation in the evaporator, produces the 90 desired cooling effect.

Although our improved device may be made of various sizes, and for use in refrigerators or cooling chambers of many different forms, we have selected, for purposes 95 of illustration, forms adapted for use in the household sizes of refrigerators.

In Fig. 1 there is illustrated a refrigerator in which the evaporator forms a central vertical partition between storage chambers 10 100 upon opposite sides thereof, and containing suitable shelves for the support of the articles to be cooled. This form of evaporator as shown more particularly in Figs. 2, 3 and 4, includes an upper tank or receiver 11, a 105 lower tank or receiver 12, and a plurality

of substantially vertical pipes 13 arranged in substantially the same plane and extending from the upper to the lower receiver.

As shown, the lower receiver 12 has an annular space 14 with which at least some of the tubes communicate, and encircling a freezing chamber 15 which is open at one end. Within this freezing chamber 15 are placed one or more trays 16 adapted to receive the water to be frozen. Preferably each tray is subdivided by a series of vertical partitions 17, so as to form a plurality of compartments whereby the water is frozen into small blocks adapted for table use, or to put into ice pitchers or drinking glasses. With the chambers 12 and 15 circular in form the freezing chamber 15 may have two of these trays 16, and each may occupy approximately one quarter of the available space in the freezing chamber, the two trays being of quarter-circular form in cross-section. The trays may be provided with suitable handles 18 whereby they may be drawn out when ice is desired, or it is necessary to refill them.

As one important feature we provide the evaporator with means whereby the return pipe from the evaporator may be automatically connected with the lower part of the receiver 12 at desired intervals to draw off liquid from the latter. As shown the receiver has only a single pipe connection 19 adapted to lead through the condenser to the boiler absorber. This pipe connection or conduit leads to a trap 20 in which scale or solid particles passing through the pipes may collect without danger of interfering with the operation of the valve hereinafter described. From the upper end of the trap a passage 21 leads laterally and connects with a passage 22 opening into the upper side of the receiver 11. At the lower end of this passage there is a valve seat 23 and a vertically movable valve 24. The valve is connected to the arm or lever 25, one end of which is pivoted at 26, and the other end carries a float 27.

A pipe 28 leads upwardly from the lowermost portion of the evaporator, and connects with the passage 22 intermediate of the ends of the latter. The valve 24 has a stem portion 29 slidable in the passage 22, and substantially closing the latter except for a small passage 30 along one side of the valve stem, and leading upwardly from the valve. The valve stem 29 has a second passage 31 lengthwise thereof, and this at its lower end communicates with a port 32 in the side of the valve stem. The port is so positioned that when the valve stem is in raised position and in engagement with the seat 23, the port 32 will communicate with the pipe 28, but when the valve stem is lowered to normal position with the valve away from the valve seat, the port 32 will be closed by the side wall

of the tube 22, as indicated in dotted lines in Fig. 4.

In the operation of our improved device the liquefied gas is delivered from the still and through the condenser and enters the evaporator through the pipe 19. The float is now in lowermost position, as shown in dotted lines in Fig. 2. When the evaporator has been substantially filled with liquid the float will rise and close the valve 24 and open the port 32. Any further liquid which is delivered may pass into the evaporator through the pipe 28. As soon as the heat is shut off at the still and the absorbing action begins, the resulting suction will be through the pipe 28 from the evaporator, and this will be assisted by the pressure on the liquid in the evaporator caused by the collection of gas in the upper part of the chamber 11 and resulting from evaporation of the liquid and the absorption of heat from the refrigerator. The liquid level in the evaporator will rapidly lower until the float opens the valve 28. Thereafter the gas resulting from the evaporation can escape directly through the passage 30, and the pipe 28 will cease to function. This operation will continue until all or the desired amount of the liquefied gas has been evaporated, and the heat is again turned on to the still to stop the absorbing and begin the distilling action. It will be noted that during each operation of the apparatus a small quantity of the liquid will be withdrawn from the lowermost portion and returned directly through the pipe 19, and the condenser, to the absorber. Thus the heavier and less volatile liquid which settles at the bottom of the evaporator, will each time be turned off and the accumulation of such non-volatile liquid in the evaporator will be prevented.

In the construction shown in Figs. 5 to 8 inclusive, there is shown a somewhat different arrangement or receivers and pipes for the evaporator. The upper receiver 11^a is connected to a very much smaller lower receiver 12^a, and these two receivers or tanks and the connecting pipes 13^a are adapted to lie against the back wall of the refrigerator. The lower receiver 12^a has a pair of cylindrical concentric spaced walls 33 and 34 extending forwardly therefrom at one end, and forming an annular chamber 14^a communicating with the main lower tank 12^a. Within the inner wall 34 is a freezing chamber 15 for the trays 16. The pipe 28^a leads from the lowermost portion of the lower receiver, and the flow through it is controlled by mechanism the same as that previously described.

In Figs. 9, 10 and 11 we have illustrated a form of evaporator particularly adapted for use in the ice box of the ordinary refrigerator. The evaporator has a large upper receiver 11^b which is connected to the lower receiver 12^b by two sets of pipes 13^b and 13^{bb}.

The larger number of pipes is used because of the smaller length and the nearness of the two receivers to each other. In this construction we have not illustrated any ice-making trays, but have shown the lower receiver 12° connected by a pipe 28° to the side of the pipe 22 and controlled by a valve similar to that previously described, but the details of which are not illustrated in this form.

It will of course be evident that there may be various other forms and arrangements of the receivers and pipe connections within the spirit of our invention, and within the scope of the appended claims.

Having thus described our invention, what we claim as new and desire to secure by Letters Patent is:

1. An evaporator having a supply pipe for liquefied refrigerant, a branch pipe therefrom to the lowermost portion of the evaporator, a float within said evaporator, and valve mechanism operated by said float for controlling one of said pipes.

2. An evaporator having a supply pipe for liquefied refrigerant, a branch pipe therefrom to the lowermost portion of the evaporator, a float within said evaporator, and valve mechanism operated by said float for opening one of said pipes and closing the other when the liquid level in the evaporator reaches a predetermined point.

3. An evaporator having a supply pipe for liquefied refrigerant, a branch pipe therefrom to the lowermost portion of the evaporator, a float within said evaporator, and valve mechanism operated by said float for opening the branch pipe and closing the first mentioned pipe when the liquid level in the evaporator reaches a predetermined level.

4. An evaporator having a supply pipe for liquefied refrigerant, a branch pipe therefrom to the lowermost portion of the evaporator, a float within said evaporator, and valve mechanism operated by said float for closing the first mentioned pipe when the liquid in the evaporator accumulates to a predetermined elevation.

5. An evaporator having a conduit connected thereto and serving for the delivery of liquid refrigerant and for the return of gaseous refrigerant, a conduit leading from the lowermost portion of the evaporator, a valve for controlling the flow of liquid from the body of the evaporator through said last mentioned conduit, and a float for controlling said valve.

6. An evaporator for intermittently operating refrigerating apparatus of the absorption type, including a liquid chamber, a conduit for delivering liquid refrigerant thereto and withdrawing gaseous refrigerant therefrom, a conduit leading from the lower portion of the liquid chamber, means for

establishing communication between said second mentioned conduit and said first mentioned conduit, a valve for controlling the flow through said second mentioned conduit, and a float for operating said valve. 70

7. An evaporator for intermittently operating refrigerating apparatus of the absorption type, including a liquid chamber, a conduit for delivering liquid refrigerant thereto and withdrawing gaseous refrigerant 75 therefrom, a conduit leading from the lower portion of the liquid chamber, means for establishing communication between said second mentioned conduit and said first mentioned conduit, a valve in said connection, and a float for opening said valve and permitting direct flow of liquid from the lower portion of said chamber to said first mentioned conduit upon reduction in pressure in said first mentioned conduit, if the 80 liquid level in said chamber be above a predetermined point.

8. An evaporator for an intermittently operating refrigerating apparatus of the absorption type, including a container for 90 liquefied refrigerant, a single conduit connected to the upper part thereof for delivering said liquefied refrigerant during the heating period and for withdrawing gaseous refrigerant during the absorbing period, 95 a second conduit leading from the lowermost portion of said container, a float within said container, and means controlled by said float for establishing communication between said second mentioned conduit and 100 said first mentioned conduit whereby liquid from the lowermost portion of said container is delivered through said second mentioned conduit to a point from which it may be sucked from the evaporator through 105 said first mentioned conduit at the beginning of the absorption period, if the liquid level in said container be above a predetermined point.

9. An evaporator for an intermittently 110 operating refrigerating apparatus of the absorption type, including a container for liquefied refrigerant, a single conduit connected to the upper part thereof for delivering said liquefied refrigerant during the 115 heating period and for withdrawing gaseous refrigerant during the absorbing period, a second conduit leading from the lowermost portion of said container, and means for establishing communication between said second mentioned conduit and 120 said first mentioned conduit whereby liquid from the lowermost portion of said container is delivered through said second mentioned conduit to a point from which it may be sucked from the evaporator through 125 said first mentioned conduit at the beginning of the absorption period, if the liquid level in said container be above a predetermined 130 point.

10. An evaporator for an intermittently operating refrigerating apparatus of the absorption type, including a container for liquefied refrigerant, a single conduit connected to the upper part thereof for delivering said liquefied refrigerant during the heating period and for withdrawing gaseous refrigerant during the absorbing period, a second conduit leading from the lowermost portion of said conduit, and means responsive to varying conditions in said container whereby liquid is delivered from the lowermost portion of the chamber through said second mentioned conduit to be sucked from the container through said first mentioned conduit, or gas may be sucked directly from the upper portion of the chamber through said first mentioned conduit.

11. An evaporator for an intermittently operating refrigerating apparatus of the absorption type, including a container for

liquefied refrigerant, a single conduit connected to the upper part thereof for delivering said liquefied refrigerant during the heating period and for withdrawing gaseous refrigerant during the absorbing period, a second conduit leading from the lowermost portion of said container, and float operated means responsive to varying conditions in said container whereby liquid is delivered from the lowermost portion of the chamber through said second mentioned conduit to be sucked from the chamber through said first mentioned conduit, or gas may be sucked directly from the upper portion of the container through said first mentioned conduit.

Signed at Scranton in the county of Lackawanna and State of Pennsylvania this 15th day of January, 1923.

STUART OTTO.
JACK CARL JANKUS.
